UNITED STATES PATENT OFFICE.

CESAR FONTANA, OF NEW YORK, N. Y.

IMPROVEMENT IN CARVING-TOOLS.

Specification forming part of Letters Patent No. **150,948**, dated May 19, 1874; application filed October 21, 1873.

To all whom it may concern:

Be it known that I, CESAR FONTANA, of the city, county, and State of New York, have invented certain Improvements in Carving-Tools, of which the following is a specification:

This invention relates to that class of implements employed in carving wood, and especially where the groundwork is cut away so as to raise objects or figures in relief; and it consists of two or more chisels placed on the body of the tool so as to abut against a projecting shoulder, and held in position by set-screws; one of the chisels being a sharp knife-edge, for cutting the wood; another being a serrated chisel, for indenting the wood; and a third a square-edged chisel or stop, placed between the knife-edge and serrated chisels, but a little back of their cutting-edges, for the purpose of regulating the depth of cut of the instrument, by means of which the rusticated or groundwork of the figure in relief is cut to an even depth, and the figure itself sharply defined, thereby enabling a boy to perform the work, and produce better work than where several tools are used separately for such purpose, as I will further explain by reference to the accompanying drawings, in which—

Figure 1 represents a side elevation of my invention; Fig. 2, a sectional view; and Fig. 3, an end view. Fig. 4 represents a portion of a picture-frame and the work thereon performed by my improved carving-tool.

A is the picture-frame; B, the figure in relief; (which is sketched by the workman previous to cutting); and C is the rusticated groundwork, cut by the tool D, said tool being composed of the knife-edged cutting-chisel E, for cutting the surface of the wood; the serrated chisel F, for breaking up and removing the wood cut by the chisel E; the square-ended stop G, for regulating the depth of cut; and the set-screws *h h*.

What I claim is—

The combination of the knife-edged chisel E, serrated chisel F, adjustable stop G, and set-screws *h h* of the carving-tool D, constructed, arranged, and operating substantially as described.

In testimony whereof I have hereunto set my signature this 21st day of November, 1871.

CESAR FONTANA.
